UNITED STATES PATENT OFFICE.

EDWARD W. STODDARD, OF DETROIT, MICHIGAN.

MACHINE FOR SEAMING ELBOWS.

SPECIFICATION forming part of Letters Patent No. 236,918, dated January 25, 1881.

Application filed October 8, 1880. (No model.)

To all whom it may concern:

Be it known that I, EDWARD W. STODDARD, of Detroit, in the county of Wayne and State of Michigan, have invented an Improvement 5 in Machines for Seaming Elbows, of which the following is a specification.

The nature of my invention relates to certain new, and useful improvements in that class of machines by means of which the seams 10 or joints of stove-pipe elbows are locked and completed. The machine is designed to complete such joints of the elbows on the inside thereof, so as to have a plain smooth surface upon their outside surface, and to be employed 15 in the manufacture of what are known as "curved" elbows.

The invention consists in the peculiar construction, arrangement, and operation of the various parts, as more fully hereinafter 20 described.

Figure 1 is a perspective view of my improved machine as seen when in use. Fig. 2 is a longitudinal central vertical section. Fig. 3 is an elevation, showing the reverse side of 25 the plunger. Fig. 4 shows the inner face of a section of an elbow, showing the parts of sheet metal which form the same, and put together ready for the machine to complete the lock.

30 In the accompanying drawings, which form a part of this specification, *a* represents the strips of sheet metal of which the elbow is formed. These strips, having been cut to proper shape and their edges crimped to form the locks or joints *b*, are put together, as shown, 35 preparatory to being presented to the machine for finishing.

The machine is constructed and operates as follows:

40 *A* is a table or frame, to which the bed *B* is securely and rigidly attached. This bed-plate terminates in an overhanging spheroidal-shaped head, *C*, the rear face, *c*, of which is vertical, and provided at its upper end with 45 an offset, in which is secured a steel jaw, *c'*.

D is a jaw with a front vertical face, *d*, the upper end being provided with an offset in which is secured a steel jaw, *e*, both the steel jaws being in vertical line with the respective vertical 50 faces of the parts *C* *D*, to which they are attached. The jaw *D* is secured to the front end

of the slide *E* and held in place by the boxes *F*, through which the slide or shaft *E* has a reciprocating movement, being actuated in its forward movement by depressing the free end 55 of the treadle-lever *G*, which draws the rod *H* downward and straightens the links *I* to a horizontal plane. One pair of these links is pivoted to the rear end of the slide *E*, and the other pair to the rear end of the bed *B*, while 60 their inner ends are pivoted together and to the top of the rod *H*. When the pressure is removed from the treadle-lever *G* the coil-spring *J* lifts the lever, thereby elevating the rod *H* and throwing the links *I* into the position 65 shown in the drawings, which communicates a retrograde motion to the slide *E* and the jaw *D* thereto attached.

K is a plunger, the lower face or edge of which is curved to suit the face of the head *C*. 70 This plunger is pivotally secured to the lever *L*, one end of which is pivoted to the standard *M*.

A rod, *N*, pivoted at its lower end to the lever *O*, passes through an eye in the outer 75 end of the lever *L*, and its upper end is provided with a nut or stop, *h*, between which and the lever *L*, and surrounding the rod *N*, is placed the coil-spring *P*.

The lever *O* is pivoted at one end to a fixed 80 point, *Q*, while the opposite end is secured to the treadle-lever *G*, so that the depression of said last-named lever will simultaneously move forward the jaw *D* and bring down the plunger, and the pressure being relieved the 85 springs *J* and *P* compel the opposite motions.

The plunger, in order to secure a true vertical movement, is provided with two vertical slots, *i*, through which bolts pass to the curved standards *R*, which are secured to the bed *B*. 90

In practice the joint *b* is laid between the jaws *c'* and *e*, (the elbow sliding over the head *C*,) when pressure upon the treadle-lever *G* forces the jaw *D* forward, thereby compressing the joint *b* between the steel jaws *c'* and *e*, 95 while the same movement brings the lower edge of the plunger down upon the joint or seam in the elbow, thereby keeping the outer face thereof perfectly smooth.

What I claim as my invention is—

1. In an elbow-seaming machine, the combination, with the fixed head *C* and horizontal

5 tally-reciprocating head D, both adapted to support and be inclosed in a pipe-elbow with the seam between them, of the vertically-reciprocating head K, and mechanism, substantially as described, whereby the reciprocating heads are operated simultaneously, substantially as described, and for the purpose set forth.

2. The combination of the head C, having
10 the jaw c, slide E, provided with the jaw d,

toggle joint I I, rod H, and treadle-lever G, with the plunger K, lever L, rod N, and lever O, secured at its outer end to the treadle-lever, whereby the slide and plunger may be simultaneously operated, substantially as described, and for the purpose set forth. '5

EDWARD W. STODDARD.
